INSERT FEED

Waldo E. Rosebush, Millwood, Wash.

Application January 2, 1937, Serial No. 118,874

8 Claims. (Cl. 270—51)

This invention relates to a device designed and adapted for use in conjunction with a sheet-folding machine, for the purpose of inserting suitable matter, such as bills, invoices, slips containing addresses, circulars, advertising folders, etc., between folds of the sheets as they are folded one at a time by said machine.

The principal object of the invention is to add to the usefulness of a folding machine of the indicated character and, at the same time, facilitate the stuffing or insertion of suitable matter together with folded sheets into window and other envelopes, and between folds of sheets to be inserted in envelopes and those folded sheets themselves constituting mailable folders.

The nature of the invention and its distinguishing features and advantages will appear when the following specification is read in connection with the accompanying drawings, in which—

Fig. 1 is a fragmentary side view showing certain features of a folding machine selected to illustrate the device of the present invention shown applied thereto;

Fig. 2 is a vertical section;

Fig. 3 is an end view;

Fig. 4 is a view similar to Fig. 2 on an enlarged scale and illustrating the manner in which an insert is introduced between the folds of a sheet as it is being folded;

Fig. 5 is a perspective view of a fold pocket constructed in accordance with the invention;

Fig. 6 is a perspective view of an insert of a type fed by the device of the present invention.

In the present instance the device of the present invention is shown, by way of example, in use in conjunction with certain features of a folding machine of the type disclosed in my pending application Serial No. 64,862, filed by me February 20, 1936.

The machine includes a main roller 10, auxiliary rollers 11, 12 and 13, respectively, and fold pockets 14 and 15, respectively. The arbors of the several rollers are journaled in bearings embodied by standards 16. Each of the auxiliary rollers 11, 12 and 13 is resiliently mounted as shown. All of the rollers rotate on horizontal axes. Each auxiliary roller being resiliently mounted will exert proper folding pressure in conjunction with the roller 10 and also to properly advance the sheets being folded. Between the rollers 11 and 12 and the rollers 12 and 13, in order to deflect the leading edge of each sheet into the related pocket 14 or 15 as the sheet is being advanced, there is provided a deflector

17 supported at the ends by plates 18 which are adjustably mounted on the sides of the standards 16, respectively. The deflectors are half round in cross section between the ends thereof overlying the roller 10. The deflectors 17 cooperate with all the rollers and the fold pockets 14 and 15 in folding the sheets. Each of the fold pockets is made preferably of a single piece of sheet metal so as to provide a flat fold plate or member 19 and a back check plate or member 20 joined to the plate 19 by a grooved bight 21. The lower edge portion 22 of the plate 20 is curved forwardly so that the mouth of the bight will be flared to readily receive the leading edge of the sheet. Each pocket is suspended on a rod 23 which extends through lugs 24 upstruck from the plate 19, said rod having its opposite ends supported, respectively, in bearings 25 adjustably secured to the standards 16 respectively. In the present instance the folding mechanism 20 illustrates the folding of a letter sheet of paper 8½ inches wide by 11 inches long, the sheet being given two folds spaced approximately equidistantly transversely of the longitudinal axis of the sheet.

The device of the present invention will now be described. A plate 30 is mounted on legs 31 secured as at 32 to the standards 16. The plate 30 is disposed at an angle of approximately 45° or, in other words, extends forwardly and downwardly toward the fold pocket 15. The plate 30 is adapted to support the pieces of material hereinabove enumerated in stacked formation, which pieces are to be fed one at a time in timed accord with the folding of the sheets one at a time. The pieces of material to be inserted are designated 33 and the sheet being folded is designated 34. Guides 35 are adjustably mounted on the plate 30, the latter being provided with slots 36 and the guides 35 carry clamping elements 37 for this purpose. Each of the guides 35 includes a piece of sponge rubber 38 or the like to contact the edges of the material 33 to prevent the same from accidentally sliding down. A transverse rod 39 is supported by the guides 35. Arms 40 are mounted on the rod 39 spaced from the guides 35 by spacers 41 on the rod 39. The lower ends of the arms 40 rest on the uppermost insert 33 to keep it straight as it is being fed or advanced. The arms 40 are adjustable with the guides along the rod 39. The inserts 33 are fed by a feed pad 42 connected with the lower ends of arms 43 loosely connected with a rocker 44 supported for rocking motion by bearings 45 secured to the under side of the plate 30. The rocker 44 is operat-

ed by a pitman 46 having one end connected with the rocker 44 as at 47 and its opposite end connected as at 48 with an adjustable cam 49 fixed on one of the arbors of the roller 10, as shown most clearly in Fig. 1. A bracket 50 is secured to each of the legs 31. A feed roller 51 is resiliently supported by the brackets 50 as at 52. The roller 51 operates with the auxiliary roller 12. A feed roller 53 is supported as at 54 by the brackets 59 and this roller cooperates with the roller 51. The rollers 51 and 53 are disposed below the plate 30 adjacent the plate or wall 20 of the pocket 15. The arrows in Fig. 4 indicate the direction in which the various rollers rotate. Deflecting means are arranged above and below the rollers 51 and 53 to guide the inserts 33 from the stack to the rollers 51 and 53, and from the latter into the fold pocket 15. In the present instance the deflecting means consists of a plate 20 55 swingable on the shaft of the roller 53 and a deflecting bar 56 secured to the legs 31.

In accordance with the invention the fold pocket 15 has an elongated opening 57 in its plate or wall 20. The opening 57 extends parallel to the pivot rod 23 and the axes of the rollers 51 and 53. A guard lip 58 is formed in continuation of the wall 20 along the lower side of the opening 57. The deflector 56 guides the leading edge portion of the insert through the opening 51, 30 and said insert rides on the lip 58 as shown in Fig. 4. The fold pocket 15 has limited pivotal movement in opposite directions, and is under tension by virtue of a tension device 59 which cooperates with a downturned and inwardly bent portion 60 of the rod 23. This spring tension is desirable due to the stiffness of the paper resulting from the paper being folded upon itself.

The fold pocket 14, in conjunction with the rollers 10, 11 and 12 and the adjacent deflector 17, produces the first fold in the sheet 34, and the pocket 15, in conjunction with the rollers 10, 12 and 13 and the deflector 17 between the rollers 12 and 13, produces the second fold in the sheet 34. As shown in Fig. 4, the second fold is about 40 to be made in the sheet 34. The device of the present invention operates in timed accord with the sheet-folding mechanism. The pad 42 is moved forward with each one-half revolution of the cam 49 and thereby advances the uppermost inserts 33. The leading edge of the insert engages the deflector 55, which guides it to the pinch of the rollers 51 and 53 which advance the insert downward. The leading edge of the insert is deflected by the bar 56 through the opening 57 into the pocket 15. The insert is approximately 3 1/4 inches wide in order to lie between the first and third folds of the sheet 34. The insert is carried with the folded sheet to be enclosed in a suitable envelope.

From the foregoing it will be understood that the objects of the invention may be attained with the device of the present invention hereinabove described. It is to be understood that certain details of the invention may be modified or rearranged without departing from the spirit of the invention in accordance with the appended claims.

I claim:

1. The combination with a sheet folding mech-

anism including a fold element into which each sheet is partly projected in the folding operation, said fold element having an opening therein; of a device for feeding unfolded pieces of material one at a time through said opening between folds of each sheet as it is being folded by said mechanism. 5

2. The combination with a sheet folding mechanism including a fold element of inverted U shape into which each sheet is partly projected in the folding operation, said fold element having an opening in one wall thereof; of a device for feeding pieces of material one at a time through said opening between folds of each sheet as it is being folded by said mechanism. 15

3. A device for feeding pieces of material one at a time between the folds of a sheet as it is being folded, said device including a support on which the pieces of material are stacked, a feed member which advances one piece of material at 20 a time, and deflecting means which direct the pieces between said folds as aforesaid.

4. A device for feeding pieces of material one at a time between folds of a sheet as it is being folded, said device including cooperative feed 25 rollers, and a deflector to direct each piece of material in a desired direction as it is received from the action of said rollers.

5. A device including a fold element of inverted U shape, said fold element having an 30 elongated opening in one wall thereof, and a guard lip in continuation of said wall extending along the lower side of said opening.

6. A device for feeding pieces of material one at a time between folds of sheets as the latter 35 are being folded one at a time, including a support on which the pieces of material are stacked, a feed member operable to advance one piece of material at a time, a pair of cooperative feed rollers, and deflecting means above and below 40 said rollers which direct the pieces from the support to said rollers and from the rollers between said folds as the sheets are fed by said feed member.

7. The combination with a sheet folding mechanism including a sheet folding pocket having limited pivotal movement in opposite directions, said pocket being of inverted U formation and its pivot being disposed a suitable distance below the closed end thereof, said pocket having an 45 elongated opening in one wall thereof paralleling the pivot, of a device for feeding pieces of material one at a time through said opening into 50 said pocket so as to be inserted between folds of each sheet as it is being folded by said mechanism. 55

8. A device for feeding inserts one at a time between the folds of each sheet as the sheets are being folded one at a time by a folding mechanism, said device including an inclined support 60 on which said inserts are stacked, a feed member operable to advance one insert at a time from said stack, cooperative feed rollers below said support at one end thereof, and deflecting means above and below said rollers which direct 65 the inserts from the support to said rollers and from the rollers between said folds as the inserts are fed by said feed member.

WALDO E. ROSEBUSH.
